Design of the HandleDesign of the HandleLetter Patented May 1, 1866.Design of a Handle

The schedule referred to in the Letter Patent and making part of the same
will show it may concern.

Be it known that Charles E. Hines, of New Haven,
in the County of New Haven, and State of Connecticut, has invented a new
and original design for Cigar Handle, and I do hereby declare the same
to be taken in connection with the accompanying drawings in
which the same is marked thereon to represent, class and exact size,
form, the same and every detail, drawing, constitute part of the description
and representation.

Fig I perspective view with the handle raised.Fig I a front view with the handle dropped.

This design relates to a Cigar Handle composed principally
of Masonic emblems, and consists of the representation of the Masonic porch
ment on which, upon either side of the altar stand the two columns supporting
the gables, and a pedestal rising from the two columns incircumscribed by a
circle, and on the pedestal the square and compass and the letter C. This
gives the socket for the handle to the time of which the handle is hinged
as will be seen in the accompanying illustrations. This design and idea is
to use for the handle to the time of which the handle is hinged

the design for a Cigar Handle herein illustrated and described.
